FOOD STORAGE DISH

Robert H. C. M. Daenen, Erembodegem, Belgium, assignor to Dart Industries Inc., Los Angeles, Calif.

Filed Apr. 23, 1973, Ser. No. 353,269

Term of patent 14 years

Int. Cl. D7—01

U.S. Cl. D7—76

FIG. 1

FIG. 2

FIG. 3

FIG. 1 is a side elevational view of a food storage dish showing my new design;

FIG. 2 is a top plan view thereof; and

FIG. 3 is a bottom plan view thereof.

I claim:

The ornamental design for a food storage dish, substantially as shown.
